UNITED STATES PATENT OFFICE.

WILLIAM V. ORR, OF CLEVELAND, OHIO.

SWITCH HOUSING.

Application filed May 27, 1921. Serial No. 473,099.

To all whom it may concern:

Be it known that I, WILLIAM V. ORR, a citizen of the United States, residing at Cleveland, in the county of Cuyahoga and State of Ohio, have invented a certain new and useful Improvement in Switch Housings, of which the following is a full, clear, and exact description, reference being had to the accompanying drawings.

10 This invention relates to electric switches and has for its objects the provision of a water proof and weather proof housing adapted for the reception of a standard type of switch and to enable its ready operation, 15 while preventing the access of water or other foreign matter to the switch parts or leakage of electricity to the casing. My improved switch casing has been devised primarily for use in connection with domestic electric machinery such as clothes washing and dish washing machines, which must be maintained at all times in operative condition notwithstanding the spilling and slopping of water and which must be safe for inexperienced persons and free from danger of accidental injury to children. However, I find it of much value in connection with other household electric devices such as stoves, ironing machines, refrigerating apparatus and also various outdoor switches and for marine work.

In the drawings accompanying and forming a part of this application I have illustrated one physical form in which my inventive idea can be embodied although it will be understood that many changes in design and appearance can be made without departing from the scope of my invention. Fig. 1 represents a side elevation of one form of my improved switch casing; Fig. 2 is a longitudinal sectional view thereof; and Fig. 3 a transverse sectional view corresponding to the line 3—3 of Fig. 2.

Describing the parts by reference characters 1 and 2 represent a pair of hollow metal members, the former having at one end an elongated neck 3 and the latter a neck 4. The last named neck is employed for the purpose of supporting the switch casing by being inserted into an aperture of the receiving member, although other supporting means can obviously be employed. The portion of each casing member opposite its neck is formed in a manner to be detachably connected to the other member in water-shedding relation, the member here illus-

trated as having exterior flange 5 adapted to overlap the other member and to be secured thereto by means of radial screws 6.

The end of the neck 3 is formed with an internal flange 8 traversed by the reciprocable member 9 whose inner end is formed with an enlarged head 10 adapted to prevent the withdrawal of such member. Rigidly secured to the outer end of the member 9 is an operating head 12 provided with a depending collar 13 loosely surrounding the neck 3 in shielding relation. The length of the collar 13 is greater than the length of the movement of the member 9 so that the joint between the parts is covered at all times.

The shape of the casing interior depends upon the shape of the switch with which the same is to be used. In the present embodiment the switch is indicated in dotted lines in Fig. 2 and in full lines in Fig. 3, the essential parts consisting of a body 15 of insulating material having at one end the lead wires 16 which pass through the neck 4 and having at the other end the push button 17 projecting into the neck 3. The switch here chosen for illustrative purposes is of the push type, having a spiral portion 18 adapted to be rotated by pressure upon the button 17 thereby advancing the ratchet 19, which by means of a suitable pawl 20 advances a pair of contact members 21—21 through 90 degrees of arc at each revolution whereby one depression of the button will bring said members into engagement with the fixed contact members 22 carried by the switch body and connected to the wires 16, and the next movement will terminate the engagement between them. It will be understood that I do not restrict myself to this type of switch either as respects the reciprocation of the button as contradistinguished from a rotation thereof or as regards the making and breaking contacts by means of an inward movement only.

Preferably the interior of the casing is lined with insulating material as shown at 20 and the neck with insulating material as shown at 21, in addition to which the head 10 is preferably provided with an insulating projection 22 which presses against the button 17 thereby keeping all parts away from metal contact.

It will be understood that many changes in design can be made and that I accordingly limit myself in no wise except as spe-

cifically recited in the claims hereto annexed.

Having thus described my invention that I claim is:

1. In a device of the character described, 5 the combination with an electric switch of the push-button snap type, of a housing surrounding said switch and having a neck in alignment with and surrounding the button, said neck having an internal flange at 10 its upper end, a reciprocal member traversing said flange and having at its inner an enlarged head adapted to bear against said button, and an operating head carried by said member outside said flange and having 15 an elongated shielding portion surrounding said neck in all reciprocal positions of said member.

2. A casing for an electric switch comprising a pair of hollow members each having a neck and adapted to receive an electric 20 switch of the push-button snap type with its operating member projecting into one neck, and its connecting wires traversing the other neck, means for securing said members detachably together, and a switch operating 25 member at all times surrounding and overlapping that neck into which the corresponding member of the switch projects and having a part operatively engaging such switch member.

In testimony whereof, I hereunto affix my signature.

WILLIAM V. ORR.
